UNITED STATES PATENT OFFICE

GEORGE F. MCKENNEY, OF CLEVELAND, OHIO

WALL CONSTRUCTION

Application filed October 15, 1930, Serial No. 488,905. Renewed May 4, 1932.

My present invention relates to wall constructions and the elements thereof, and more particularly to a novel side wall, ceiling, partition or the like, adapted to serve as a finished 5 wall surface or as a base for a plaster coating.

More particularly the invention contemplates a novel combination of studding, wallboard, and means for securing the wallboard 10 to the studding.

The invention also provides a novel type of stud and a new clip to serve as means for supporting the wallboard against the studding.

15 Among the important objects of the invention are the following: To provide an assembly of wallboard elements closely associated together in end to end relation to form a wall or ceiling; to maintain such assembly securely supported in place; to minimize the width of the openings between the edges of adjacent wallboard elements; to prevent sagging of the wallboard from the foundation studding or scantling; to provide a construction which 20 may be assembled in a minimum of time, by relatively unskilled labor, and which will require only inexpensive and easily handled parts; to provide an installation which will be entirely fireproof; and in general to provide a novel wall or ceiling structure which 25 will be superior to those of the prior art.

The elements which make up the combination constituting the complete exposition of the present invention may be used in the construction of a vertical side wall or a ceiling. 30 It is to be understood that the invention is capable of embodiment in either of such structures. Merely to exemplify the invention, the accompanying drawings show it reduced 35 to practice in a ceiling structure. In the following specification and claims the term "wall" will be used, and it is to be understood that this term is intended to include generically a vertical side wall, a ceiling, a partition, or any other of the surfaces of building interiors which are commonly faced with a plaster coating.

40 The invention, which is illustrated in certain preferred forms of embodiment in the accompanying drawings, will now be ex-

plained briefly and later pointed out in the claims.

In the accompanying drawings which form part of this application for Letters Patent and in which the same reference numeral designates the same part in the several views, 55

Figure 1 is a vertical sectional view of a wall, roof and ceiling structure;

Fig. 2 is a similar vertical section taken at a right angle to the view of Fig. 1; 60

Fig. 3 is a bottom plan view of the structure shown in Figs. 1 and 2; or Fig. 3 may be considered an elevational view of a vertical wall or partition;

Fig. 4 is a side elevational view of one of 65 the stud elements of the wall showing the plasterboard and pin in section;

Fig. 5 is a bottom plan view of a stud;

Fig. 6 is a cross sectional view of a stud 70 and its associated plasterboard taken on line 6-6 of Fig. 4;

Fig. 7 is a view similar to Fig. 6 but showing a modification; and

Fig. 8 is a perspective view of a modified 75 type of clip and pin showing these two elements formed integrally with each other.

Referring now to the drawings, and first to Figs. 1 and 2, the reference numeral 1 designates a roof or floor structure which in the form shown in the drawings is of 80 reinforced concrete construction. It is to be understood that the invention which is now to be described may be associated, when embodied in a ceiling, with any well known type of roof or floor construction.

85 Secured to the under side of the roof are eyes or the like 2 from which depend wire links 3 or equivalent means for suspending any suitable type of beam 4. In the form shown in the drawings the links 3 are hung in spaced rows along the roof and carry a plurality of beams 4 in parallelism. It will be appreciated that the beams may be of any suitable type, and any desirable means for suspending them may be employed. Furthermore, the distance between adjacent beams will depend largely upon the dimensions of other parts of the structure, the preference of the individual designer, and other considerations.

The reference numeral 5 designates one of a plurality of studs which are secured by any satisfactory means, such for example as the twisted wire 6, preferably at right angles across the parallel series of beams 4. Thus it will be evident that if the beams 4 in a given installation extend longitudinally of the room or building, the studding 5 will extend transversely of the room or building.

11 Figs. 4 to 7 inclusive show detail views of the novel stud 5 which forms one of the elements of the present invention. The stud is channel shaped, being provided with a back face 8 and integral right angularly extending parallel sides 9. The stud is provided at regular intervals along its length with pairs of transverse bridges 10, for a purpose which will now be explained.

12 The stud is secured, as has been explained, 20 to the beams 4 with its back 8 engaged with the lower surfaces of the beams, so that its sides 9 extend toward the interior of the room. Wallboard 11 is applied to the studding preferably in the form of strips of the 25 usual commercial size, i. e., 48 inches by 16 inches. When boards of these dimensions are used the studding elements are conveniently spaced 2 feet apart, and the wallboards are placed transversely of these studding elements so that each board will contact along 30 its transverse edges with studding strips and will engage across its transverse center line another studding strip.

13 With the wallboard elements applied as shown in Fig. 3, a clip 12 is used to secure the wallboards to the studding strip. This clip, which is best shown in Fig. 4, consists of a length of wire having hooked end portions 13 and an intermediate loop 14, besides 40 a waved portion 15 which is intended to provide spring resiliency in the clip. The dimensions of the clip are such that its end portions 13 may be sprung over each of an adjacent pair of transverse bridges 10 of the 45 studding, and its loop 14 will project through the space formed between adjacent edges of the wallboards, to receive a pin 16 and hold said pin snugly against the margins of the wallboard. As shown in the drawings this 50 pin may conveniently be an ordinary carpenter's nail.

14 The wallboard having been applied as explained in connection with the description of Fig. 3, a plurality, preferably two or three, 55 of clips 12 and pins 16 are associated with the transverse bridges and the wallboard margins, as has been explained. Preferably the wallboard is preformed with slots 17 extending in a series, conveniently three in number, across its transverse center line. When installed, these slots 17 register with one of the studs, so that clips may be inserted through one or more of these slots to engage 60 the transverse bridges of the stud and

pins 16 to support this central portion of the wallboard element.

While the transverse bridges 10 may be provided in any suitable way on the channel stud, I prefer to form the stud of sheet metal 70 and to strike out of the free edges of its side portions integral ears which are directed inwardly toward the opposite side of the channel stud. Preferably, but not necessarily, these integral metal ears are struck in pairs 75 oppositely from both sides of the channel so that a two-ply transverse bridge is provided, as shown in Fig. 5. Such expedient has the advantage of increased strength and better resists the bending stresses incurred in supporting the weight of the wallboard.

80 The transverse bridges 10 may conveniently be provided along the stud at constant, uniform distances, i. e., so that the distances between the bridges of each pair and the distance between the adjacent bridges of two consecutive pairs are substantially equal, so that the clip 12 need not necessarily be applied to the pair of bridges designated A, A, 85 in Fig. 5, but may, if desired, be disposed between any other consecutive pair, such as the bridges A, B.

85 It will be evident that the feature just described greatly facilitates assembly of the wall elements by rendering it unnecessary for the workman to select any particular pair of bridges to be engaged by a given clip.

90 Fig. 7 illustrates a modification in which a short length of wire 18 is substituted for the clip 12. According to this modification the wire is inserted through the space between the wallboard edges, looped over one of the transverse bridges 10, and over a pin 16, and then twisted to secure the pin across the edges 95 of the wallboard. The twisted ends of the wire 18 may be tucked up in the space between the wallboards.

95 Fig. 8 shows a modification of the preferred type of clip and pin illustrated in the other figures. According to the modification of Fig. 8, the clip and pin are made integral, being conveniently stamped out of a single piece of sheet metal. As will be evident from Fig. 8, the clip portion of the modification follows in general the contour and shape of the wire clip 12 of Figs. 4 and 6, and is provided with a pair of integral, outwardly extending ears 19 corresponding to and serving the same function as the pin 17. The clip of Fig. 8 is also provided with a pair of hooked end portions 20 adapted to engage the transverse bridges 10 of the stud and an intermediate waved portion 21, corresponding respectively to the portions 13 and 15 of the clip 12.

100 It is to be understood that the wall surface, when assembled as has been described, may, if desired, be covered with a plaster coating (not shown). Indeed, one of the principal uses of the invention is to serve as 105

a foundation surface for plaster, providing a substitute for the well known metal or wooden lathing, which is at once superior in point of efficiency and cost of construction.

5 It is well known that the wallboard 11 (which may be the usual plaster or gypsum slab provided with an exterior coating of paper or paste board) is capable of forming a close bond with plaster. I have found that 10 such wallboard when hung according to the principles of the present invention provides a base for the reception of a plaster coating which eliminates several of the objectionable characteristics of wallboard foundations as 15 assembled prior to this invention. Thus, by the present invention the cracks between adjacent boards are reduced to a minimum, since they need be no wider than the diameter of the wire of the clip. Cracks of such reduced 20 width are negligible, so that the foundation wall constitutes a practically unbroken expanse of wallboard having the advantage of a uniform "suction" or rate of absorption, which results in the prevention of cracking in 25 the drying plaster.

Again, the resilience of the clip serves to maintain the wallboard securely and snugly against the studding, preventing the warping, loosening and consequent shifting thereof 30 of which is inevitable when the boards are fastened to the studding by non-yielding or non-resilient means, such as nails and the like.

While I have shown the elements 11 in the drawings as the well known plaster or gypsum 35 board and have in the specification and claims denominated them "wallboard", it is to be understood that their precise character and composition is not material to the present invention. Thus, while I prefer to use paper 40 covered and generally imperforate gypsum board, the wallboard elements 11 may be of wood, metal or any other suitable material, and may be foraminous, as may be desired. In other words, the term "wallboard" as used 45 in this specification and in the claims is intended to include within its extension any acceptable type of preformed wall covering material which is adapted to be used as a finished wall surface or as a base for plaster.

50 It is to be understood that I have shown and described in this application for Letters Patent the present invention in certain preferred forms of embodiment merely by way of exemplification. Other and further modifications will occur to persons skilled in the art, but all such modifications, to the extent that they embody the principles of the present invention as pointed out in the appended claims are to be deemed within the scope and 55 purview thereof.

Having thus described my present invention what I claim and desire to secure by Letters Patent is:

60 1. A wall construction including wall- 65 board, a stud of channel cross section pro-

vided with a pair of spaced apart transverse bridges, a clip having end portions engaged with said bridges and an intermediate portion adapted to project between abutting edges of the wallboard, and an element engaged by said intermediate portion and supporting adjacent margins of the wallboard. 70

2. A wall construction including wallboard, a stud of channel cross section provided with a pair of spaced apart transverse bridges, a spring clip having end portions engaged with said bridges and an intermediate portion projecting between abutting edges of wallboard, a pin engaged by said intermediate portion and yieldingly pressed thereby against the marginal portions of the wallboard. 75

3. A wall construction as claimed in claim 1, in which the sides of the channeled stud extend toward the wallboard and portions of one of said sides are struck out and turned inwardly toward the other side to form the transverse bridges. 80

4. A wall construction as claimed in claim 1, in which the sides of the channeled stud extend toward the wallboard and portions of both of said sides are struck out and directed inwardly toward the opposite side in contacting relation to provide a two-ply transverse bridge. 85

5. A wall construction as claimed in claim 1, in which the sides of the channeled stud extend toward the wallboard and in which the transverse bridges are formed on the free edges of said sides. 90

6. A wall construction as claimed in claim 1, in which the channel stud is provided with a plurality of pairs of transverse bridges, the distances between the bridges of each pair and between the bridges of adjacent pairs being substantially equal. 105

7. A wall construction as claimed in claim 2, in which a portion of the clip between its end portions is waved or curved to increase its resiliency. 110

8. In a wall construction, the combination of a stud having a pair of spaced bridges extending across its transverse dimension, and means for carrying a wallboard supporting pin from said bridges. 115

9. A stud for a wall construction comprising a channel shaped member having a back and two substantially parallel sides, a portion of the free edge of one of the sides being struck out and inwardly directed toward the opposite side to provide an integral, transverse bridge, adapted to receive and carry a wallboard supporting clip. 120

10. A stud for a wall construction comprising a channel shaped member having a back and two substantially parallel sides, portions of the free edges of both of the sides being struck out and directed inwardly toward the opposite side to provide a two-ply transverse 125

bridge, adapted to receive and carry a wall-board supporting clip.

11. A stud for a wall construction comprising a channel shaped member having a back and two substantially parallel sides, portions of the free edge of one of the sides being struck out and inwardly directed toward the opposite side at a plurality of points to provide a plurality of integral, transverse bridges, adapted to receive and carry a wall-board supporting clip.

12. A stud for a wall construction comprising a channel shaped member having a back and two substantially parallel sides, portions of the free edge of one of the sides being struck out and directed toward the opposite side at a plurality of points, and portions of the free edge of the other side being similarly struck out and directed toward the first side at a plurality of opposite points, the opposite struck out portions being disposed in contacting parallelism to provide a plurality of transverse bridges, adapted to receive and carry a wallboard supporting clip.

25 In testimony whereof I affix my signature.

GEORGE F. McKENNEY.
